UNITED STATES PATENT OFFICE

JOHN V. SHOEMAKER, OF DETROIT, MICHIGAN

DESIGN FOR A WIPER FOR OIL GAUGES

Application filed March 17, 1930. Serial No. 34,933. Term of patent 7 years.

To all whom it may concern:

Be it known that I, JOHN V. SHOEMAKER, a citizen of the United States, residing at Detroit, in the county of Wayne and State of Michigan, have invented a new, original, and ornamental Design for Wiper for Oil Gauges, of which the following is a specification, reference being had to the accompanying drawing, forming part thereof.

I claim:

The ornamental design for a wiper for oil gauges as shown.

JOHN V. SHOEMAKER.
